UNITED STATES PATENT OFFICE.

HUGO LENTZ, OF BERLIN-HALENSEE, GERMANY.

FLUID-OPERATED POWER-TRANSMISSION APPARATUS.

1,156,787.

Specification of Letters Patent. Patented Oct. 12, 1915.

Application filed October 27, 1914. Serial No. 863,873.

To all whom it may concern:

Be it known that I, HUGO LENTZ, a citizen of the German Empire, and resident of Berlin-Halensee, Germany, have invented 5 certain new and useful Improvements in Fluid-Operated Power-Transmission Apparatus, of which the following is a specification.

My invention relates to improvements in 10 fluid operated power transmission apparatus, and more particularly in power transmission apparatus in which a suitable fluid, ordinarily a non-elastic fluid, is forced from a prime mover in the form of a rotary pump 15 and driven by an engine to a secondary mover in the form of a rotary fluid operated motor connected with the driven member such for example as the propeller shaft of a ship. In apparatus of this class such 20 as are now in use the efficiency is low by reason of the complicated path of the passages connecting the pump and the motor.

The object of the improvements is to provide an apparatus of this class which has a 25 high efficiency.

With this object in view my invention consists in so constructing the apparatus that in normal operation the fluid flows along a most simple path and through passages of substantially constant width.

For the purpose of explaining the invention an example embodying the same has been shown in the accompanying drawing, in which the same letters of reference have 35 been used in all the views to indicate corresponding parts.

In said drawing Figure 1, is a vertical cross-section of the apparatus, taken on the line 1—1 of Fig. 2, and Fig. 2, is an axial 40 section of the same.

In the example shown in the drawing the power transmitting apparatus consists of a set of pressure pumps A and A' and a set of 45 motors B located with its axis parallel to the axis of the pumps. The pumps and motor are of the rotary type and the rotary drums thereof which carry the pistons or blades are rotatably mounted within bushings H, H', and I respectively which are 50 fitted in bores made in a casing C. The set of pumps is secured to a shaft D, for ex-

ample the shaft of a turbine, and the set of motors is secured to a shaft F, for example the propeller shaft of a ship. If desired the said shafts are independently mounted 55 and connected respectively with the driving engine and the driven member by a suitable coupling.

In the example shown in the drawing the set of pumps consists of two single acting 60 pressure pumps A and A', and the size and effect of the pump A is the double of that of the pump A', so that by throwing either one of the pumps or both of them into operation the driven member is driven at three 65 different speeds. As shown the set of motors consists of a single member B. The motor as well as the pumps are of the rotary types, and they comprise rotary drums each carrying radially reciprocating blades or 70 pistons and lateral cams and guide rollers for imparting reciprocating movement to the pistons.

Between the set of pumps A and A' and the set of motors B controlling members or 75 valves K and L are provided the axes of which are likewise disposed parallel to the axes of the pumps and motor. As shown the valves are in the form of cock valves and their lengths are equal to the lengths of the 80 drums of the pressure pumps and motors. The cock valve K is the regulating valve. The cock valve L is used in conjunction with the valve K for reversing the direction of the flow of the fluid to the motor and the 85 direction of rotation of the motor.

In the position of the valves K and L shown in the drawing the motor is driven in forward direction, the set of pumps rotating in the direction of the arrow. The 90 pressure fluid flows from the working chamber R of the pistons of the pump and through a port h and the open cock valve K into a pressure passage N, from which it is supplied to the working chamber O of 95 the motor. Finally it is discharged into a suction passage P, from which it is returned through the open reversing cock valve L, a chamber Q and a port h' to the pump. The valve K also controls the connection of a 100 chamber M with the passage N and with a circumferential by-passage Q' leading to the

suction chamber Q. The valve L also controls the connection of said chamber M with the motor passage P and the suction chamber Q. The passages N, P, which connect the motor with the pump, are of substantially constant width, and the ports or ways of the valves K, L, as well as the chambers M, Q, and the by-passage Q', are of a width equal, or nearly equal, to that of said passages N, P.

By turning the cock valve K in a clockwise direction the passage of the fluid to the pressure passage N can be throttled and the by-passage Q' leading to the suction chamber Q opened, so that only a part of the driving fluid is supplied to the motor B, the remainder being directly returned to the pump. Thereby the speed of the motor can be reduced as desired. In order that the valve K may assume a position such as just described, in which the chamber M and the passages N and Q' are all three open to the valve port or valve way at the same time, the arc of the solid portion of the valve must be greater than the "land" between the ports communicating with the passages N and Q', yet smaller than the aggregate width of said ports and of the "land" between them, so that the valve may take a position in which both of said ports are throttled while the third port (leading to M, h) is fully open. By turning the cock valve K so far that the pressure passage N is entirely closed and the by-passage Q' entirely open, the whole current of the fluid is directly returned to the suction side of the pump without flowing through the motor, so that the speed of the motor is zero. Finally by setting the valves K and L in the positions shown in dotted lines the power medium can be made to act on the motor B in the opposite direction. In this case the pressure fluid flows through the port h and the chamber M into the passage P which before was the suction passage and which now is the pressure passage, so that the fluid acts on the pistons of the motor in the opposite sense, whereupon it flows through the passage N and the by-passage Q' to the pump. Thereby the motor rotates in the reverse direction.

From the description of the operation of the apparatus it will readily be understood, that in the normal operation, that is when the motor is running in forward direction, the power fluid is discharged from the pressure pumps in the form of a wide band corresponding in width to that of the pump, and that the width of the current is not changed when the fluid flows through the controlling valves and the motor, so that the current is in the form of a continuous oval band of constant width. Therefore the efficiency of the apparatus in case of the normal operation is high, because the direc-

tion of the flow of the fluid and the width are not changed.

While in describing the invention reference has been made to an example in which the pressure pump consists of two sections and the motor of a single section, I wish it to be understood that my invention is not limited to the construction shown in the drawing, and that various changes may be made in the general arrangement and construction of the parts without departing from the invention.

I claim herein as my invention:

1. The combination of a rotary pump having suction and delivery ports, a suction chamber connected with said suction port, an auxiliary or delivery chamber connected with said delivery port, a by-passage extending circumferentially of the pump and connected with said suction chamber, passages each adapted to serve as a suction passage or as a delivery passage, a valve controlling the connection of one of said passages with the suction chamber and with the auxiliary chamber, and another valve controlling the connection of the other passage with the delivery chamber and with the by-passage.

2. The combination of a rotary pump having suction and delivery ports, two passages each adapted to serve either as a suction passage or as a delivery passage, two connections leading from each of said passages, one to the suction port of the pump and the other to the delivery port thereof, and valves controlling said connections, one of said valves having its rotary solid portion greater circumferentially than the land between the respective passage and the connection to the suction port, yet smaller than the aggregate width of said passage and connection and of the land between them, whereby said valve may be turned into a position in which it throttles said passage as well as said suction connection while leaving the corresponding delivery connection fully open.

3. The combination of a rotary motor, a rotary pump having suction and delivery ports, a suction chamber connected with said suction port, an auxiliary or delivery chamber connected with said delivery port, a by-passage connected with said suction chamber, suction and pressure passages connected with said motor, a valve controlling the connection of said suction chamber with said auxiliary chamber and with said suction passage, and another valve controlling the connection of said auxiliary chamber with said by-passage and with said pressure passage, the last-named valve having its rotary solid portion greater circumferentially than the land between said pressure passage and said by-passage, yet smaller than the aggregate width of said land and

of the ports leading to said pressure passage and by-passage respectively, whereby said valve may be turned to a position in which it throttles said pressure passage as well as said by-passage while leaving the connection to the auxiliary chamber fully open.

In testimony whereof, I have signed this specification in the presence of two subscribing witnesses.

HUGO LENTZ.
